No. 640.

M. C. Burleigh: Design for door and panel of booting store
Patented April 25, 1904—

Fig. 4.

Dec. 640

M. C. Burleigh, of Great Falls, N. H.
Letters Patent No. 640 - Dated April 25th, 1852.

The schedule referred to in these Letters Patent, & making part of the same.

To all whom it may concern:

Be it known that I, M. C. Burleigh, of Great Falls, in the County of Strafford, and State of New Hampshire, have invented a new and ornamental design for the doors and panels of cooking stoves; and I do hereby declare that the following is a full, clear, and exact description of the same, reference being had to the accompanying drawing, forming part of this specification.

Fig. 1 is a front view of a stove door ornamented with my new design.

Fig. 2 is a profile view of the same.

Similar letters of reference in each of the two figures refer to like parts.

A, represents a stove door, having mouldings f, g, formed round it as shown in Fig. 2. It also has a central ornament which is encircled by a bead, a. This ornament is composed of nine gourd shaped projections b, b, b, b, b, b, b, b, b, which are arranged in a circle within the bead, a, around a quirked ovolo shaped seat c, formed in the center of the door or panel of the stove, in the manner shown in Figs. 1 and 2. The seat, c, terminates in a small circular bead, d. Within this bead, a small spherical projection e, is formed, as shown in the drawing.

B. B. Fig. 1, represent rays striking out from the central ornament; these rays form a square, as shown in the drawing. Fig. 1.

What I claim as my invention, and desire to secure by Letters Patent, is the arrangement and combination of the central ornament a, b, c, d, & e, with the rays B, and mouldings f, g, substantially as described and shown in the drawing, for the purpose of forming a new ornamental design for a cooking stove.
